SELF SEALING CAP FOR COLLAPSIBLE CONTAINERS

Filed Jan. 27, 1933

UNITED STATES PATENT OFFICE

2,015,602

SELF-SEALING CAP FOR COLLAPSIBLE CONTAINERS

Benno B. Leustig, Cleveland, Ohio

Application January 27, 1933, Serial No. 653,895

17 Claims. (Cl. 221—60)

The present invention relates to self-sealing caps for collapsible containers, and may be considered in the nature of an improvement with respect to the cap assembly disclosed in my copending application Serial No. 567,231, filed October 6, 1931.

The primary object of the invention, therefore, is to improve the cap assembly of my prior application.

10 Another object is to provide a cap assembly which is economical to manufacture and which can be easily and quickly assembled for shipping or for direct application to a tube in assembled condition.

15 Another object of the invention is to provide a cap assembly which can be readily applied to the necks of tubes as used for the conventional screw-thread type of cap.

20 Another object of the invention is to provide a lock for caps of this type which is efficient in performing its function yet so simple in construction that the additional cost involved in production is almost negligible, a factor of considerable importance where the article must be sold in large quantities at a relatively low price.

25 Another object of the invention is to provide a lock for a self-sealing cap assembly which not only serves as a simple and efficient lock but also serves as a convenient means for holding the parts in assembled position when packed for shipment and/or when applied to the necked extremity of the tube.

30 The foregoing and other objects and advantages will become apparent in view of the following description taken in conjunction with the drawing, wherein:—

35 Figure 1 is a view in side elevation of a preferred form of my self-sealing cap assembly applied in operative position to a collapsible tube; Fig. 1a shows the guard or retainer ferrule removed; Fig. 1b shows the assembly in section with the cap in the position it assumes when extruding the contents from the tube; Figs. 1c, 1d and 1e show the respective parts of the assembly in perspective, and Fig. 1f is a detail perspective view of the assembly ready for application to a tube or for shipment to be subsequently applied to a tube.

40 Fig. 2 is a view similar to Fig. 1 of the lock as made in conjunction with a modified form of cap assembly; Fig. 2a is a transverse vertical sectional view thereof; Fig. 2b is a horizontal section taken on the line indicated in Fig. 2a; and Figs. 2c and 2d are detail views of parts of the assembly.

45 Figs. 3, 4 and 5 are horizontal sectional views,

taken substantially as in Fig. 2b, of modifications in lock construction; and

5 Figs. 6 and 7 are views in transverse vertical section of slight modifications in the assembly shown in Figs. 2 to 2c, inclusive.

Referring in detail to the drawing, and first to Figs. 1 to 1f, inclusive, 5 designates a collapsible container or tube, 6 a retaining guard or ferrule, 7 a valve cap which fits over the end of the tube and is held in assembled position by the ferrule 6, and 8 a resilient member or spring which is positioned between the cap and guard and contacts at its lower end a stop flange 7a formed on the cap and at its upper end a stop flange 6a formed on the guard or ferrule 6. The end of 10 the tube is formed with a neck 5a at the base of which an enlargement or shoulder 5b is provided. The top wall of the neck is formed with one or a plurality of outlet orifices 5c and a rounded tip 5d. The top of the cap 7 is formed with an outlet 15 orifice 7b, and this orifice is closed by the tip 5d when the cap is in normal retracted position with the surrounding wall of the cap sealing the orifices 5c. It will be noted that there are no separate compartments or pockets which segregate 20 portions of the substance in the tube and permit such portions to harden or become dry and render extrusion difficult if not impossible.

25 The foregoing construction is disclosed in substance in my prior application above noted, with 30 the exception that in my original assembly, the ferrule is provided with a plurality of resilient flanged fingers which engage in a groove formed at the base of the neck of the tube and hold the ferrule in assembled position. I have found 35 that if means are provided for giving the ferrule a press fit, cost of manufacture and assembly of the parts can be materially reduced. Hence, I provide the enlarged annular portion or shoulder 5b and simply press the ferrule in position 40 on this shoulder when assembling. Moulding of the tube is thus simplified, since there is no groove or threaded portion to be formed around the neck, and stamping of the guard or ferrule is also simplified, since there are no flanges required. Furthermore, very light metal can be 45 used, since there is no snap engagement or resilient spring action involved.

An important feature of the present invention is a lock construction, which consists in 50 forming a depression 10 in the wall of the ferrule 6 adapted (in the form of the assembly just described) to coact with the flange 7a of the cap 7. This depression is substantially L-shaped with its one leg 10b slightly inclined upwardly 55

and at its lower end terminates in a stop lug 10a. The flange 7a is recessed or formed with a gap 11 of sufficient width to permit the leg 10b of the depression 10 to pass freely therethrough.

5 In assembling, the parts may be assembled as a separate unit as shown in Fig. 1f, the spring 8 simply being inserted over the cap 7 and the guard or ferrule 6 placed over the cap and spring with the depression 10 and gap or recess 11 in 10 registration. It is now only necessary to push the cap into the ferrule until the flange 7a passes the leg 10b of the depression 10, whereupon the cap is turned slightly and the flange locks over said leg, being urged thereagainst by 15 the spring 8. The assembly is then ready for shipment and/or for application to the tube 5. The ferrule 6 may be given a press fit with the fingers, or a suitable tool may be employed.

After the ferrule 6 has been pressed onto the 20 shoulder 5b, the cap 7 is turned back until the leg 10b registers with the gap 11, whereupon the spring 8 urges the cap down into sealing position, as shown in Fig. 1.

To lock the cap 7 in sealing position, it is only 25 necessary to give it a slight turn so that the flange 7a engages under the leg 10b, the lug 10a acting as a stop to show when the cap is locked. The cap may be knurled, as at 12, to facilitate 30 turning thereof.

It will be noted that the tube neck requires 35 no threading or outwardly projecting portions to cooperate with the cap assembly. This simplifies the process of manufacture of the tube, as will be readily understood by those having a knowledge of the art. The lock structure requires no extra parts and is so simple in construction as to render its cost almost negligible.

In Figs. 2, 2a and 2b, the cap assembly 40 comprises a sealing or valve cap 13, a nozzle tip or member 14 and spring 8. The cap 13 is provided with an extrusion orifice 13a and lower turned fingers 13b. The tip 14 is provided with outlet orifices 14a which are sealed by the valve cap 13 when the latter is in normal 45 retracted position. This tip 14 is a member separate with respect to the tube and is preferably adapted to have a press fit on the neck 5a. Thus the tube may be the same as that used for the conventional screw-thread cap with the 50 threads omitted, which feature reduces the cost of production of the tube. This tip may, however, be interiorly screw-threaded, in which event the same may be substituted for the conventional screw-threaded cap when applying the 55 assembly.

In assembling, the nozzle member 14 may be inserted in the cap, then the spring 8, after which 60 the fingers 13b are turned in, and the assembly is complete ready for application to the neck of the tube.

In this instance the lock consists of a depression 10' formed in the side wall of the valve cap 13 and having an inclined locking leg 10c which is adapted to engage under a locking lug 16, formed on the neck of the tube, when the cap is turned toward the right as viewed in the drawing. A stop lug 17 is also formed on the neck of the tube, to indicate by "feel" when the valve cap is in open position.

70 In this form of the device also, the parts may be assembled and shipped and applied as a separate unit. While there are projecting parts, namely the lugs 16 and 17, formed on the tube neck, yet I have found that these are very easy to form and add substantially nothing to the

cost of manufacture. The stop lug may be omitted if desired, as will be obvious. The lugs and depression do not interfere with the action of the spring 8. The assembly as a whole may be applied by simply pressing the nozzle tip 14 on the tube neck.

In Figs. 3 to 7, inclusive, certain modifications in structure relative to Figs. 2, 2a and 2b are shown.

Fig. 3 shows a lock construction wherein a stop lug 17a is formed on the tube neck 5a and a coacting stop boss 17b is provided on the nozzle cap 13. Locking is effected by a lock lug 16a formed on the neck 5a, which lug coacts with an inclined locking flange 18 formed at 15 the one extremity of the flange 13b. Stop 17b contacting lug 17a indicates locked position, while contact with lug 16a indicates unlocked position.

In Fig. 4, the lock construction is substantially the same as in Fig. 3 with the exception that 20 it is simplified, there being stop means to indicate when the cap 13 is in unlocked position only, stop boss 17a being omitted. When cap 13 is turned to the right, flange 18 engages under lug 16a, and when it is turned to the left, stop 17b 25 contacts with lug 16a, indicating unlocked position.

In Fig. 5, the structure is reversed relative to Fig. 3, stop bosses 17c and 17d being formed in the cap 13 and being adapted to contact with 30 lock lug 16a on the tube neck 5a. Stop boss 17d contacting with lug 16a indicates locked position, while boss 17c contacting with said lug 16a indicates unlocked position. Bosses 17c and 17d are simply depressions in cap 13. 35

In Fig. 6, the cap 13 is provided with a separate flange member 19 which is given a press fit in the lower end of the cap, the latter being slightly offset to provide a smooth inner surface and a stop shoulder for the flange member 19. This construction eliminates the separate operation of turning in spring-retaining fingers or a flange on the cap 13.

In Fig. 7, the construction is substantially the same as in Fig. 6 with the exception that 45 flange member 19a is longer and a modification in lock structure is shown. In this instance, the edge of the tip or nozzle member 14 is formed with a locking notch 20 having a stepped portion 20a therein which forms a stop. A locking 50 boss 21 is formed on the cap 13 or member 19a, depending upon which type of cap is used, said boss engaging in notch 20 when the cap is turned to locking position. To unlock the cap, the latter is pulled clear of notch 20 and turned until 55 boss 21 engages in notch 20a.

It will be noted that the lock construction in each instance has been developed with a view toward providing an efficient lock with the greatest possible ease in manufacture. It requires 60 very little additional effort to merely stamp the bosses 10, 17b, 17c, 17d in the wall of the ferrule 6 or cap 13, and the lugs 16, 17, etc. are relatively small and may be readily cast on the neck 5a of the tube 5. In both the guard and valve 65 cap type of assembly, the parts may be assembled and shipped and applied as a unit by a simple press fit, which type of fit lends itself readily to automatic machine or tool manipulation and with relatively simple machinery or tools. It will 70 be noted, further, that in each of the forms shown, the means for holding the assembly in position on the tube is adapted to have a press fit on a reduced or necked portion of the tube, said means in the form shown in Figs. 1 to 1f 75

being the guard or ferrule 6, while in the remaining figures the nozzle tip 14 serves this function, and this same means also serves as an abutment for one end of the spring.

5 I claim:—

1. In combination with a collapsible container having a reduced neck portion at the extrusion extremity thereof, a self-sealing cap assembly comprising a valve cap, resilient means for normally urging said cap to sealing position, and means having a press fit over said neck portion for holding the resilient means in operative position with respect to the valve cap when the latter is forced from its seat and also for holding the assembly in position on said neck portion.

10 2. In combination with a collapsible container having a reduced neck portion at the extrusion extremity thereof, a self-sealing cap assembly comprising a valve cap, a spring for normally urging said cap to sealing position, and means having a press fit over said neck portion for holding the assembly in position thereon, said means providing a shoulder against which one end of the spring abuts for holding the spring 15 in operative position with respect to the valve cap when the latter is forced from its seat.

20 3. In combination with a collapsible container having a reduced neck portion at the extrusion extremity thereof, a self-sealing cap assembly comprising a valve cap formed with an outlet orifice at one end thereof and spring-retaining means at its opposite end, a spring for normally urging said cap to sealing position, the one end of said spring abutting against said 25 means, and means adapted to be secured to said neck portion for holding the cap and spring in operative position on said neck portion, said means providing an abutment for the other end of said spring.

30 4. In combination with a collapsible container having a reduced neck at the extrusion extremity thereof, a valve cap fitting over said neck, resilient means for normally urging said cap to sealing position, a retaining ferrule fitting over said spring and cap to complete the assembly, and means for locking said cap in sealing position, said means also serving to lock the cap against displacement with respect to the ferrule.

35 5. In combination with a collapsible container having a reduced neck at the extrusion extremity thereof, a self-sealing cap assembly comprising a valve cap having an outlet orifice at one end and a flange at its opposite end, a spring for normally urging said cap to sealing position, a retaining ferrule for holding the spring in operative position with respect to the cap and also for holding the assembly on said neck, and locking means comprising a substantially L-shaped boss formed on said ferrule and having 40 an inclined leg adapted to engage under the flange of said cap.

45 6. In combination with a collapsible container having a neck at the extrusion extremity thereof, a self-sealing cap assembly comprising a valve cap formed with an outlet orifice at one end thereof and a flange at its opposite end, said flange being formed with a gap, a spring for normally urging said cap to sealing position, said spring being positioned on said cap with its lower end abutting against said flange, a ferrule fitting over said spring and cap and provided with a flange at one end thereof adapted to engage the opposite end of said spring, and a substantially L-shaped locking boss formed in the 50 side wall of said ferrule, said boss having an in-

clined leg adapted to pass through said cap, the extremity of the flange which lies adjacent said gap being adapted to engage under said leg when it is desired to lock the cap in sealing position and to engage over said leg when it is desired to lock the cap against displacement with respect to said spring and ferrule.

65 7. In combination with a collapsible container having a reduced neck portion at the extrusion extremity thereof, a self-sealing cap assembly comprising a valve cap having an outlet orifice at one end thereof and a flange at its opposite end, said flange being formed with a recess or gap therein, a retaining ferrule having a flange at one end thereof, said ferrule fitting over said spring and cap and being secured to the extremity of the tube, and means serving both as a lock for the valve cap and for holding the cap against displacement with respect to the ferrule and spring, said means comprising a de- 70 pressed boss formed in the side wall of the ferrule and having a substantially vertical leg and a slightly inclined leg, said inclined leg being adapted to be passed through said recess or gap and selectively engage on either side of the flange.

75 8. In combination with a collapsible container having a reduced neck portion at the extrusion extremity thereof, a self-sealing cap assembly comprising a valve cap having an outlet orifice at one end thereof and a flange at its opposite end, said flange being formed with a recess or gap therein, a retaining ferrule having a flange at one end thereof, said ferrule fitting over said spring and cap and being secured to the extremity of the tube, and means serving both as a lock for the 80 valve cap and for holding the cap against displacement with respect to the ferrule and spring, said means comprising a depressed boss formed in the side wall of the ferrule and having a substantially vertical leg and a slightly inclined leg, said inclined leg being adapted to be passed through said recess or gap and selectively engage on either side of the flange, the lower end of said boss terminating in a stock lug for indicating when the cap is in unlocked position.

9. In combination with a collapsible container having a reduced neck portion at the extrusion extremity thereof, a self-sealing cap assembly comprising a valve cap, a nozzle member having a press fit on said neck and formed with an extrusion orifice adapted to be closed by said cap when the latter is in sealing position, and resilient means for normally urging said cap in sealing position with respect to said nozzle member.

10. In combination with a collapsible container having a neck at the extrusion extremity thereof, a self-sealing cap assembly comprising a valve cap formed with an outlet orifice at one end thereof and a spring-abutment at its opposite end, a nozzle tip secured to said neck and formed with an outlet orifice adapted to coact with the orifice in said cap, and resilient means positioned between the abutment of said cap and said nozzle member for normally urging the cap to sealing position.

11. In combination with a collapsible container having a neck at the extrusion extremity thereof, a self-sealing cap assembly comprising a valve cap formed with an outlet orifice at one end thereof and a spring-abutment at its opposite end, a nozzle member having a pressed fit on said neck and formed with one or a plurality of outlet orifices adapted to coact with the orifice in said cap, and a spring for normally urging said cap to sealing position with respect to said nozzle.

- member, said nozzle member serving as an abutment for one end of said spring.
12. In combination with a collapsible container having a neck at the extrusion extremity thereof, said neck terminating in one or a plurality of extrusion outlet orifices, a valve cap having an outlet orifice adapted to coact with said extrusion orifices, a spring for normally urging said cap to sealing position with respect to said extrusion orifices, and means for locking said cap in sealing position, said means comprising a substantially L-shaped depression formed in the side wall of said cap and coacting lugs formed on the side of said neck, one of said lugs being adapted to engage said depression and hold the cap against relative longitudinal movement with respect to said neck and another of said lugs serving as a stop lug to indicate when the cap has been turned to unlocked position.
13. In combination with a collapsible container having a neck at the extrusion extremity thereof, a self-sealing cap assembly comprising a valve cap having an outlet orifice at one end thereof and a flange at its opposite end, said flange being formed with a gap or recess therein, a spring for normally urging said cap to sealing position, and means for locking said cap in such position comprising a locking lug formed on said neck and adapted to clear said gap when the cap is moved longitudinally to unseated position and to engage the flange when the cap is slightly rotated with respect to the tube.
14. In combination with a collapsible container having a neck at the extrusion extremity thereof, a self-sealing cap assembly comprising a valve cap having an outlet orifice at one end thereof and a flange at its opposite end, said flange being formed with a gap or recess therein, means for normally urging said cap to sealing position, and means for locking said cap in such position comprising spaced depressions formed in said cap and adapted to contact a locking lug formed on said neck and indicate locking and unlocking positions, said lug being adapted to engage under an inclined portion of said flange adjacent said
- recess when the cap is slightly rotated with respect to said tube.
15. In combination with a collapsible container having a neck at the extrusion extremity thereof, said neck being formed with a locking lug and a stop lug, a valve cap adapted to be positioned on said neck and formed with an outlet orifice at one end thereof and a retaining flange at its opposite end, said flange being formed with a gap or recess therein and an inclined extremity 5 adjacent said recess, and a stop boss formed in the side wall of said cap and adapted to contact with said stop lug and said locking lug to indicate when the cap is turned to locked and unlocked position, said inclined extremity of the 10 flange engaging under the locking lug when the cap is slightly rotated with respect to said tube, thereby locking the cap against longitudinal movement with respect to said neck.
16. In combination with a collapsible container 20 having a neck at the extrusion extremity thereof, a self-sealing cap assembly comprising a nozzle member having a pressed fit on said neck, a valve cap adapted to fit over said nozzle member, a spring for normally urging said cap to sealing position, said nozzle member serving as an abutment for one end of said spring, and a separate flange member having a pressed fit in the lower 25 end of said cap for serving as an abutment for the opposite end of said spring.
17. In combination with a collapsible container having a neck at the extrusion extremity thereof, a self-sealing cap assembly comprising a nozzle member secured on the end of said neck, a valve cap adapted to have a sliding fit on said nozzle 30 member, means for normally urging said cap to sealing position on said nozzle member, and means for locking said cap in such position, said means comprising a locking lug provided in the side wall of said cap and adapted to engage in a recess formed in the edge of said nozzle member when the cap is slightly rotated with respect to said latter member.

BENNO B. LEUSTIG.
